US00D746032S

(12) **United States Design Patent**
Marvin et al.

(10) **Patent No.:** US D746,032 S
(45) **Date of Patent:** ** Dec. 29, 2015

(54) **SHOE**

(71) Applicant: **Reebok International Limited**, London (GB)

(72) Inventors: **William Marvin**, Canton, MA (US); **Matthew Montross**, Middleboro, MA (US)

(73) Assignee: **Reebok International Limited**, London (GB)

(**) Term: **14 Years**

(21) Appl. No.: **29/470,409**

(22) Filed: **Oct. 21, 2013**

CLAIM

The ornamental design for a shoe, as shown and described.

DESCRIPTION

FIG. 1 is a bottom plan view of a shoe showing our new design;

FIG. 2 is a side view thereof;

FIG. 3 is bottom plan view of another embodiment of a shoe showing our new design;

FIG. 4 is a side view thereof;

FIG. 5 is a bottom plan view of another embodiment of a shoe showing our new design; and,

FIG. 6 is a side view thereof.

The broken lines in the Figures show environment and unclaimed portions, and form no part of the claimed design. The dot-dashed lines in the Figures show an unclaimed boundary of the subject matter being claimed.

1 Claim, 6 Drawing Sheets
